UNITED STATES PATENT OFFICE.

GEORGE B. BRAYTON, OF BOSTON, MASSACHUSETTS, ASSIGNOR TO THE
BRAYTON PETROLEUM ENGINE COMPANY, OF SAME PLACE.

REGULATING THE SUPPLY OF OIL TO VAPOR-ENGINES.

SPECIFICATION forming part of Letters Patent No. 270,927, dated January 23, 1883.

Application filed April 10, 1882. (No model.)

To all whom it may concern:

Be it known that I, GEORGE BAILEY BRAYTON, a citizen of the United States, residing at Boston, in the county of Suffolk and State of Massachusetts, have invented certain new and useful Improvements in a Device for Regulating the Supply of Oil to Vapor-Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to means for governing the supply of oil fed to air-carburetors by a pump, whereby the supply of oil thus furnished is automatically adapted to the amount required, my invention being especially intended for use in vapor-engines employing a gas made from the vapors of petroleum or other oil rich in hydrocarbons, used with atmospheric air.

My invention consists in certain mechanical details of construction by which the length of stroke of the pump-piston is automatically changed (increased or diminished) in accordance with the amount of gas requisite to perform a given labor.

The drawings accompanying this specification represent in Figure 1 a sectional elevation, and in Fig. 2 a cross-section, of a device embodying my improvements. Fig. 3 shows the connection of the oil-pumps and the air-tank with the carburetor, and also the means whereby the air is supplied to the tank.

Reference being had to the above-named drawings, it will be seen that A represents a liquid-injecting pump of any suitable construction, while a represents the piston-rod of such pump, the outer end of this rod terminating in a tubular head, b.

B represents a second rod arranged in axial alignment with the first, and at one end entering loosely the socket or bore in the outer end of the rod a, this rod B, at its opposite end, being connected with the eccentric by which the piston is operated. The rod B plays within the rod a so loosely as of itself to effect no movements of the pump-piston; and to compel the two to move together, and thereby put the pump in operation, I employ a tapering vertical

or wedge-shaped key, c, which is contained in vertical coinciding slots d e, created longitudinally in the said rods a and B. The two slots d e constitute a common passage, which is filled to a greater or less extent by the key c, according as the altitude of the latter may vary. When it is in its lowest position the key is supposed to fill both slots, and no slip movement can take place between the two rods a B; hence the full impulse is given to the pump-plunger. As the key is raised from this position a slip movement is permitted between the two rods and the stroke of the pump-plunger is shortened to an extent corresponding to the degree of altitude of the key, and the supply of oil delivered by the pump is lessened to a corresponding extent.

To automatically change the altitude of the key c in accordance with any increase or diminution in the amount of oil consumed or required for consumption, I secure the lower end of the stem f of the key c adjustably to the tail g of a horizontal weighted lever, h, the base of which is pivoted to the dome or cap i of a diaphragm-case, j, the interior of such case being connected with the air-tank of the carburetor, with which the pump is connected by a pipe, n.

Within the case j, I secure a horizontal elastic diaphragm, k, and I erect upon and secure in a proper manner to this diaphragm a stem, l, which extends upward through the dome of the case j and supports the weight of the lever h, the weight m of the lever serving to equate the diaphragm to the pressure of the air-tank of the carburetor C to insure the drop of the key c.

If the pressure of air in the tank increases or diminishes in correspondence with the amount of gas consumed, whether driving an engine or otherwise, the diaphragm is distended, the lever and key raised, and the stroke of the pump-plunger shortened, and vice versa.

This invention is an improvement on that set forth in Patent No. 151,468, granted to me June 2, 1874, to which reference is hereby made for a fuller explanation and illustration of the air-tank, the means for supplying the same, the cause of the varying pressure, and other features which need not be here repeated.

In Fig. 3 it will be seen that the air-tank a'

is supplied with air on the upward stroke of the piston. Consequently the pressure will vary somewhat with the speed of the engine. This varying pressure would correspond exactly with the varying pressure in a steam-boiler, all depending on the amount of work being done at any given moment or period. Said pressure is transmitted from a' to the diaphragm and diaphragm-chamber through pipe 10 n , and thence to the pump.

The operation of the carburetor is the same as that shown and described in the Letters Patent Nos. 125,116 and 151,468, granted to me April 2, 1872, and June 2, 1874, respectively. Reference to said patents (and particularly to the last named) is hereby made for a fuller and more explanatory description of this device.

I claim—

20 1. In combination with the oil-supply pump and the air-tank of an air-carburetor, mechanism, substantially as described, interposed be-

tween the two, whereby the changes in pressure in such air - tank effect corresponding changes in the length of stroke of the pump-plunger to automatically accommodate the amount of oil fed by the pump to the requirements of the motor supplied with gas. 25

2. In combination with the oil-supply pump and the air-receiver of an air-carburetor, the two rods a and B , having axial play with respect to each, and slotted to receive the key c , the diaphragm-case and its diaphragm, the lever h , pivoted to the diaphragm-case and fulcrumed upon the diaphragm, and adjustably 30 secured at its tail to the stem of the key c , and the key c , playing with the slots of the rods a and B , all substantially as stated. 35

In testimony whereof I affix my signature in presence of two witnesses.

GEORGE BAILEY BRAYTON.
